(57) **CLAIM**

The ornamental design for a sheet of material for a wearable item such as a garment, vest or shirt, as shown.

DESCRIPTION

FIG. 1 is a perspective view of the sheet of material for a wearable item such as a garment, vest or shirt;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The material shown in broken lines is environment and forms no part of the claimed design.
